Application June 24, 1944, Serial No. 541,989

12 Claims. (Cl. 200—21)

1

This invention relates to ignition apparatus for the ignition system of an internal combustion engine, or the like, and more particularly to means for controlling electrical circuits and distributing electrical current impulses to a plurality of circuits.

One of the objects of the present invention is to provide novel apparatus for controlling the flow of electrical current in a plurality of connected circuits in the ignition system of an internal combustion engine.

Another object of the invention is to provide novel unitary apparatus for distributing electrical current at relatively low voltage from a plurality of sources to a larger number of branch circuits in timed sequence.

Still another object is to provide a light, compact device which is sturdy and reliable for distributing electrical current at relatively low voltage from one or more sources of electrical current to the spark plugs in the cylinders of a multi-cylinder engine.

A further object is to provide novel simplified apparatus for controlling the flow and distribution of electrical current from a plurality of current generating means to the spark plugs of an engine.

A still further object is to provide apparatus of the above character wherein the rotating parts are small and light and may be driven at relatively low speeds even in an engine having a large number of cylinders and requiring the generation of a large number of sparks during short intervals of time.

Another object is to provide novel means for mounting a spring-pressed current carrying brush of carbon or like material in a rotating or other part whereby the movement of the brush by the spring is limited.

Another object is to provide a novel simplified apparatus of the above character wherein the parts may be readily assembled and disassembled for inspection, repair and adjustment with utmost facility and wherein the surrounding casing may be readily removed to permit inspection and adjustment without disturbing the operating parts.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for

2

this latter purpose being had primarily to the appended claims.

In the drawings, wherein like reference characters refer to like parts throughout the several views,

Fig. 1 is a side elevation, mostly in section and with parts broken away and parts removed in the interest of clarity, showing one form of apparatus embodying the invention, the section being taken substantially on lines 1—1 of Figs. 3 to 7, inclusive;

Fig. 2 is a detail sectional view taken substantially on lines 2—2 of Figs. 4 to 7, inclusive, and approximately on lines 2—2 of Figs. 1 and 3 with the distributor rotor shown in full;

Fig. 3 is a transverse sectional view taken substantially on line 3—3 of Fig. 1 and showing a representative portion of the circuit breaker mechanism of the device;

Figs. 4 and 5 are end elevation detail views showing the opposite faces of a part of the device of Figs. 1 and 2, the views being taken from the left and the right, respectively, in Fig. 1;

Figs. 6 and 7 are similar views of another part of the distributor mechanism, the views being taken from the left and right, respectively, in Fig. 1.

Figs. 8 and 9 are detail side elevation views on an enlarged scale taken at nearly right angles to each other and showing novel means for mounting the distributor brushes in the distributor rotor; and,

Fig. 10 is a wiring diagram illustrating the use of the device in an ignition system.

The single embodiment of the invention illustrated in the accompanying drawings, by way of example, is adapted for use in the ignition system of an 18-cylinder four-stroke cycle internal combustion engine. It may, for instance, be employed for distributing alternate current impulses from two sources of electrical energy to a set of spark plugs in the cylinders of a double row radial type engine wherein the cylinders of one row are staggered angularly with respect to the cylinders of the other row. On such an engine the distributor rotor and circuit breaker cams of the present device may be driven at one-half engine crankshaft speed, thereby facilitating the timing of the ignition system with the cylinders.

The operating parts of the novel apparatus comprehended by this invention are encased and mounted in such a manner as to make the same readily available for inspection and repair without in any way disturbing the operating parts or the relative adjustment thereof. In the form

shown, the casing comprises a main or supporting structure 10, a central open-ended tubular member 11 slidably fitted around axially extending parts of the support 10 and a distributor and cable housing 12 fitted with a cover 13 and having a cable outlet 14. Central housing member 11 serves as a spacer between parts 10 and 12 which are removably secured together by means of a plurality of bolts 15. Housing member 10 may be secured by means of bolts 16 to the casing of an engine or to an adaptor 17 which is in turn secured to the engine casing by means of bolts 18. To provide for limited angular adjustment of the device when mounting the same on an engine, bolts 16 may extend through elongated arcuate slots 19 (Fig. 3) in casing member 10. Bolts 16 are preferably permanently mounted in the engine casing or adaptor 17 and casing member 10 is held in position by nuts 20. If desired, adaptor 17 may take the form of a housing for an automatic advance-retard mechanism or variable coupling which may be employed for coupling the present device to an engine.

A rotatable shaft 21 concentric with the arcuate slots 19 is mounted in spaced roller bearings 22, 23 provided in the framework of casing member 10. The left end of said shaft as viewed in Fig. 1 extends through adaptor 17 and is provided with a suitable gear or splined member 24 for driving engagement with a part of the engine (not shown). Drive member 24 is preferably adjustably coupled to shaft 21 by coupling means 25 of the character disclosed in Spengler U. S. Patent No. 2,266,283 so that small angular adjustments of a permanent nature may be made for ignition timing purposes. An oil seal 26 of any suitable type such as a "Gits" seal, for example, may be mounted around shaft 21 in the transverse end wall 27 of housing member 10 for preventing oil from entering the circuit breaker chamber 28 from the engine crank case or gear housing on which the apparatus is mounted. If desired, shaft 21 may have the magnetic or flux distributing rotor of a magneto generator mounted thereon and enclosed by a suitable extension of casing member 10.

In order to create periodic surges of electrical current at a suitable voltage in the spark plug circuits of an internal combustion engine for a purpose to appear hereafter, two or more circuit breaker cams 29 and 30 are keyed or otherwise suitably secured on shaft 21 for rotation therewith between bearings 22 and 23. Each of said cams as shown is of the compensated type provided with nine lobes suitably spaced for controlling the supply of electrical energy to the spark plugs of nine radially disposed cylinders in a manner well understood in the art. Two circuit breakers M1 and B1 which may be of the type shown in Shoemaker et al. Patent No. 1,866,492 are adjustably mounted on an axially extending support 32 of housing member 10 for actuation to open position by cam 29. Two circuit breakers M2 and B2 of the same type are mounted in the same manner for actuation by cam 30, said cam and circuit breakers being so mounted that the points or contacts of main circuit breakers M1 and M2 will be alternately operated in timed sequence and the points or contacts of booster circuit breakers B1 and B2 will be similarly operated but in retarded relation with respect to the operation of the corresponding main circuit breakers. One set of said circuit breakers is illustrated in Fig. 3 and the other set is shown only diagrammatically in Fig. 10, but both sets may be sub-

stantially identical. Each of the main circuit breakers has one of its points or contacts grounded through the casing heretofore described and the other contact connected with a source of electrical energy, such as a magneto generator having an induction coil operatively associated in a well known manner with a permanent magnet and a magnetic flux distributing rotor. Each of the booster breakers has both of its points or separable contacts insulated from ground and connected in the ignition circuit in a manner to appear hereafter. As shown, an insulating block 31 (Fig. 3) is employed between each booster breaker and frame member 32 which is part of casing member 10.

Tubular casing member 11 surrounds the circuit breakers and in the bottom thereof a pair of condensers 33 and 34 are suitably mounted. In the illustrated embodiment both condensers are supported by sheet metal brackets 35 secured by means of said screws to axially extending portions of frame 10 in the manner best shown in Fig. 3. Each condenser has one side thereof grounded through its casing and housing member 10 and the other side thereof connected to the ungrounded contact or point of one of the main circuit breakers, as shown in Fig. 10.

Secured to the right hand end of frame 10, as viewed in the drawings, and constituting a part 30 of the novel ignition distributor comprehended by the present invention is an insulating plate 36. For a purpose to appear more fully hereafter, the studs 37 which secure plate 36 in position extend through elongated arcuate slots 38 in said plate and, hence, permit limited angular adjustment of the plate around the axis of rotation of shaft 21. Partially embedded in insulating plate 36 and projecting from one face thereof are two concentric metallic rings 39 and 40. Said rings are connected by inserts 41 and 42, respectively, to terminals 43 and 44, respectively, which are embedded in and extend through plate 36 near the periphery thereof. The ends of terminals 43 and 44 within circuit breaker chamber 28 are connected with the insulated contacts of the main circuit breakers M1 and M2, respectively, by suitable conductors shown only in Fig. 10. Each of two additional terminals 45 and 46 having the same construction as or being similar in construction to terminal 43 is connected to one contact of each of the booster circuit breakers B1 and B2. The other contact of each of the booster circuit breakers is electrically connected to the insulated side of a main circuit breaker. 55 These connections are clearly shown in Fig. 10.

Facing plate 36 and spaced axially therefrom is a second insulating plate or distributor block 47 which extends transversely across the interior of housing member 12 and is mounted in the latter by means of stud bolts 48, only one of which is shown. Embedded in plate or block 47 and projecting from the left face thereof, as viewed in Figs. 1 and 2, are two series or sets of arcuate contacts 49 and 50 arranged in concentric circles about the axis of rotation of shaft 21. Each contact 49 of the inner circle is in radial alignment with a contact 50 of the outer circle (Fig. 6) and each of the contacts 49 and 50 is connected to or integral with a terminal post 51 that extends through block 47 to the opposite face thereof. In the illustrated embodiment there are nine contacts in each circular series. Terminal posts 51 may be counterbored to receive a terminal screw 52 for connecting a conductor or cable 53 to each of said posts. These cables conduct electrical en-

ergy to transformer coils 54, the secondary windings of which may be connected to spark plugs 55 in the engine cylinders (Fig. 10).

Embedded in block 47 near the periphery thereof and opposite terminals 43, 44, 45 and 46 in plate 36 are corresponding terminals 43a, 44a, 45a, and 46a, respectively. Means are provided for automatically electrically connecting the last-mentioned terminals in block 47 to the respective terminals in plate 36 when cover or housing member 12, 13 is moved into assembled position. In the form shown, said means in each instance comprises a relatively rigid bracket-like member 56 which has a coil spring 57 or the like secured to one end thereof for yieldable engagement with a terminal in plate 36 while the other end of said member threadedly engages a screw 58 (Fig. 2). Said screw extends through the hollow terminal embedded in block 47 and is adapted to hold an incoming conductor in electrical engagement with the terminal and, hence, with connector 56, 57.

Shaft 21 extends freely through a central opening in plate 36 and has a rotor 59, commonly known as a distributor finger, removably mounted thereon for rotation therewith, such as by means of a key 60 and a nut 61 threaded onto the end of the shaft. Said rotor or finger consists primarily of an elongated block of insulated material equipped with novel means adjacent each end thereof for continuously picking up electrical current from rings 39 and 40 and conducting the same to terminals or contacts 49 and 50, respectively, on distributor block 47. Current picked up from the outer ring 39 is conducted to the inner ring or series of contacts 49 by a pair of carbon or like brushes 62 and 63 slidably mounted in recesses in finger 59 and projecting from opposite faces thereof at different radial distances from the axis of rotation of shaft 21. The inner end of each brush has a coil spring 64 attached thereto and the free ends of the two springs are mechanically and electrically connected by a metallic strip 65 embedded in the insulation of finger 59. The springs 64 are of such length as to press brushes 62, 63 against ring 39 and contacts 49, respectively, when the parts are in assembled relation as shown in Figs. 1 and 2. Current picked up from inner ring 40 is conducted to the outer ring of contacts 50 by a pair of brushes 66 and 67 mounted in the other end of rotor 59 and connected together in the same manner as brushes 62 and 63.

Novel means are provided in combination with each of the brushes 62, 63, 66 and 67 and its associated spring for limiting the extension of the latter and thereby preventing the same from pushing the brush completely out of its recess in finger 59 when the latter is removed from shaft 21 or when housing section 12, 13 and, hence, block 47 is detached from the remainder of the housing. As shown, said means consists of two interlocked loops of wire 68 and 69 (Figs. 8 and 9). One end of loop 68 has at least one coil or turn 70 which engages one end of spring 64. The remainder of wire 68 forms a loop or bite within spring 64 and the end thereof projects outwardly through a washer 71 and conducting member 65 and is bent over and soldered in place as indicated in Fig. 9. The other loop 69 interlocks with loop 68 within spring 64 and the turned-in ends 64' thereof have interlocking engagement with a plate-like element 72 having a circumference approximately equal to the outside circumference of spring 64 and slotted to receive wire 64. Element 72 is soldered or otherwise suitably secured,

preferably in a recess 73, in the metal plated end of brush 62. The combined length of loops 68 and 69 is such as to prevent spring 64 from moving the carbon brush out of its recess in finger 59 but is nevertheless sufficient to permit the spring to press the brush firmly against the ring or contacts which it is intended to slidably engage.

By reason of the novel construction of the above-described apparatus, it is an easy matter to properly assemble the parts and to time the device to an engine during the installation thereof on the engine. For this purpose a timing mark 74 is placed on rotor 59 (Fig. 2) and four angularly spaced radial marks 75, 76, 77 and 78 (Fig. 5) are placed on the right hand face of plate or disc 36, as viewed in Fig. 1. These radial marks represent the proper position of the rotor mark 14 when the circuit breakers M1, B1, M2 and B2, respectively, are initially opened for firing the plugs in selected cylinders of the engine and are employed in a novel manner to properly assemble the apparatus and correct for the angular manufacturing tolerances allowed in connection with the positioning of the keyways on the cams and distributor rotor, and shaft 21, the positioning of the holes for bolts 37 and the like. Thus, in the process of assembly, circuit breaker M1, for example, is first adjusted so that it will be held in open position for a predetermined angular rotation of shaft 21 by the lobe of cam 29 which circles the firing in a preselected cylinder such as the number 1 cylinder of the engine. Then with the shaft and rotor 59 in the position at which the opening of circuit breaker M1 is initiated, plate 36 is angularly adjusted to bring the marks 74 and 75 in alignment, in which position said plate is firmly secured to housing member 10 by bolts 37. The remainder of the circuit breakers B1, M2 and B2 are individually adjusted on supporting arm 32 so that the contacts thereof will start opening when rotor mark 74 is in alignment with marks 76, 77 and 78, respectively. Having thus assembled the device and with the piston in the number 1 cylinder of the engine (or other pre-selected cylinder) in its firing position, the member 24 is moved into mesh with the engine driving member while the mark 14 on rotor 59 is in alignment with mark 75 on plate 36 and slots 19 are in alignment with bolts 16. This meshing and alignment may be effected through proper adjustments permitted by the adjustable coupling 25. The main circuit breaker M1 which is connected to control the firing of the spark plug in the number 1 cylinder (or other pre-selected cylinder) will then be opened by its cam 29 every second time the piston in said cylinder reaches its firing position. The other circuit breakers have likewise been adjusted by the use of marks 76, 77 and 78 so that circuit breakers M2, B1 and B2 will be opened at proper intervals and in proper timed relation with the engine. The proper angular positions for marks 76, 77 and 78 with respect to mark 74 may be readily calculated by taking into consideration the angular distances between lobes on the circuit breaker cams and between cam followers of circuit breakers operated by the same cam, the angular rotation of the engine between the firing of pre-selected successively firing spark plugs, and the positions of the cams relative to each other. It may be pointed out that both plate 36 and block 47 are provided with location notches 79 and 80, respectively (Figs. 1, 4 and 5), which mesh with suitable pins 91 and 92 or the like.

in casing member 12 to avoid improper installation of the block 47 in the casing member 12 and of said casing member on casing member 10.

The functioning of the above-described apparatus may best be understood by considering its operation in a complete ignition system, as shown diagrammatically in Fig. 10. In starting the engine on which the system is mounted, energy may be supplied by a battery 81 or other suitable source through a starter switch 82 to a pair of booster or buzzer coils 83 of any suitable known construction which periodically interrupts the direct current from battery 81. The interrupted current from one of the booster coils, for example, flows through a lead 84 to one side of booster breaker B1. This lead extends into the apparatus of Fig. 1 through opening 14 and includes the terminal 45a, a connector 56, 57 and terminal 45 in plate 36. When both breakers B1 and M1, which are operated by cam 29, are in closed position, current flows through the booster breaker B1 and the main breaker M1 to ground. When, however, breaker B1 is in closed position and breaker M1 is in open position the current flows through leads 85 and 86 to outer ring 39. It will be seen that the connection 85, 86 of Fig. 10 includes the terminal 43 and insert 41 embedded in distributor plate 36. From ring 39 this booster current flows through brushes 62 and 63 in rotor 59 to an arcuate contact 49 on block 47 and thence through a terminal post 51 and a lead 53 to a transformer coil 54, the secondary winding of which is operatively connected to a spark plug 55 as heretofore described. The flow of interrupted current through the primary winding of the coil 54 induces current impulses in the secondary winding of the coil at sufficiently high voltage to produce a shower of sparks across the gap of the spark plug. Current from the other of the pair of booster coils is conducted through booster breaker B2, ring 40, brushes 66, 67, and distributor contacts 50 in a similar manner to other spark plugs and will not be described in detail. This latter circuit, of course, includes their terminals 46a, 46 and 44 and insert 42 in that order.

When the engine is started and is running at a sufficiently high speed, current may be furnished by one or more engine driven magneto-generators, the induction coils of which are illustrated at 87 and 88 in Fig. 10. The ungrounded or high potential end of coil 87 is connected by means of leads 89 and 85 to main circuit breaker M1. The lead 89 of Fig. 10 enters the device of Fig. 1 through inlet 14 and includes terminal 43a, a connector 56, 57 and terminal 43 in plate 36. Terminal 43 is connected to the insulated side of circuit breaker M1 by lead 85. Coil 87 is also connected to ring 39 of the distributor by leads 89 and 86, the latter being represented by insert 41 in Fig. 1. When circuit breaker M1 is closed, the current flows through the breaker because this circuit contains less resistance than the parallel connected circuit of which lead 86 is a part. When the current flow is near its maximum value, main circuit breaker M1 is opened by cam 29. This results in a sudden surge of current through the circuit including lead 89, lead 86, ring 39, brushes 62 and 63, a contact 49, a lead 53, and the primary winding of a transformer coil 54. This sudden surge of current through said primary winding results primarily from self induction in coil 87 and is effective to induce a relatively high voltage in the secondary winding of the transformer coil and, hence, produce a spark

across the gap of a spark plug 55. The current impulses produced in winding 88 alternate with those produced in winding 87 and the flow thereof is controlled in a similar manner by main circuit breaker M2 and that portion of the distributor mechanism comprising ring 40, brushes 66, 67 and contacts 50 in distributor block 47.

There is thus provided a novel, simplified ignition unit for timing the electrical impulses or sparks in the ignition system of an engine and for distributing the same in proper timed relation to the spark plugs, said unit being so constructed that the rotating parts thereof may be driven at half engine speed. The novel construction of the unit facilitates the internal timing adjustments thereof and also the timing of the unit to the engine on which it is mounted. Additionally, the novel unit comprehended is adapted to be housed in such a manner as to make it easy to inspect the operating parts without disturbing said parts or their relationship to one another. Said unit is also compact and durable as well as reliable and efficient during operation. Novel means for positioning the brushes of a distributor finger in a simple and reliable manner to prevent damage thereof by careless mechanics or otherwise are also provided.

Although only a single embodiment of the invention has been illustrated, it is to be expressly understood that the same is not limited to this particular structure. Various alternative embodiments have been hereinbefore mentioned and many other variations, especially in the design and arrangement of parts illustrated, may be made without departing from the spirit and scope of the invention as it will now be understood by those skilled in the art. For a definition of the limits of the invention, reference is had primarily to the appended claims.

40 What is claimed is:

1. In ignition apparatus of the character described, a casing, a rotatable shaft journalled in said casing, two circuit breaker means each comprising a cam mounted on said shaft for rotation therewith and separable contact points adjustably mounted on said casing for periodic operation by said cams, a distributor finger mounted on said shaft for rotation therewith, an insulating plate mounted on one side of said finger in said casing for angular adjustment relative to the latter, two concentric metallic rings mounted on said block in concentric relation with said shaft, a cover removably mounted on said casing, an insulating block mounted in said cover on the other side of said finger, two concentric circles of angularly spaced metallic contacts on the face of said block adjacent said finger, a terminal post for each of said contacts extending through said block for connection with an outgoing cable, a pair of spring-pressed brushes carried by said finger at one side of said shaft for conducting current from the outermost of said metallic rings to the contacts of the innermost of said circles of contacts, and a pair of spring-pressed brushes carried by said finger at the other side of said shaft for conducting electrical current from the innermost of said rings to the outermost of said circles of contacts.

2. In ignition apparatus of the class described, a supporting member, a shaft rotatably journalled in said member, circuit breaker means including at least one pair of separable contact points mounted on said supporting member and cam means on said shaft for periodically sep-

rating said points, a tubular casing member slidably mounted on said supporting member around said circuit breaker means, a cup-shaped casing member engaging one end of said tubular casing member, means for removably securing said cup-shaped member to said supporting member, and current distributing means enclosed by said cup-shaped casing member including a current distributing rotor mounted on said shaft and a plurality of circularly arranged contacts mounted in and insulated from said cup-shaped member.

3. In an ignition distributor, a supporting member, a shaft rotatably journaled on said member, an insulating plate mounted on said member around said shaft, a conducting ring on said plate concentric with the axis of rotation of said shaft, a terminal on said plate electrically connected with said ring, a cup-shaped casing member removably mounted on said supporting member, a distributor block mounted in said casing member, a plurality of contacts on said block circularly disposed around the axis of rotation of said shaft, a terminal in said block opposite said first-named terminal, means for automatically electrically connecting said terminals when said casing member is secured in place on said supporting member, and means rotatable with said shaft for conducting electrical current from said ring to said contacts.

4. In an ignition distributor, a casing member having axially extending supporting means, a shaft rotatably journaled in said supporting means, at least one circuit breaker mounted on said supporting means, cam means on said shaft for actuating said circuit breaker, a tubular casing member slidably mounted on said supporting means and surrounding said circuit breaker, a cup-shaped casing member engaging the end of said tubular casing member and removably secured to said first-named casing member, and current distributing means enclosed by said cup-shaped casing member including at least one current conducting ring mounted on said supporting means, a plurality of circularly disposed contacts mounted in and insulated from said cup-shaped casing member and a current distributing rotor for conducting current from said ring to said contacts.

5. In an ignition distributor, a supporting member, a shaft rotatably journaled in said member, a conducting ring mounted on and insulated from said supporting member in concentric relation with the axis of rotation of said shaft, a plurality of circularly arranged contacts removably supported by and insulated from said supporting member, a current distributing rotor mounted on said shaft between said ring and said contacts, a spring pressed brush on said rotor engaging said ring, a spring-pressed brush on said rotor for successively engaging said contacts, and means electrically connecting said brushes.

6. In an ignition distributor, a supporting member, a shaft rotatably journaled in said member, an insulating plate mounted on said member around said shaft, a conducting ring on said plate concentric with the axis of rotation of said shaft, a terminal on said plate electrically connected with said ring, a distributor block removably supported by said supporting member, a plurality of contacts on said block circularly disposed around the axis of rotation of said shaft, a terminal in said block, means for automatically electrically connecting said terminals when said block is secured in place on said supporting mem-

ber, a rotor on said shaft between said block and plate, and means including spring-pressed brushes on said rotor for conducting electrical current from said ring to said contacts during rotation of the rotor.

5 7. In an ignition distributor having a rotatable current distributing assembly comprising an insulating block having axially-extending radially-spaced recesses in opposite faces thereof, a conducting brush, such as a carbon brush, slidably mounted in each of said recesses, one of said brushes projecting beyond one face of said block and the other of said brushes projecting beyond the other face of said block, and resilient means in each of said recesses tending to urge said brushes out of said recesses, of means embedded in said block and comprising an electrically conductive metallic strip having portions extending across said recesses for mechanically supporting said resilient means and for electrically connecting said brushes to each other.

10 8. In an ignition distributor having a rotatable current distributing means comprising a block of insulating material, a conducting brush, such as a carbon brush, slidably mounted in a recess in said block, and a coil spring secured to said block and brush for urging said brush outwardly in said recess, of a pair of relatively stiff interlocking loops engaging opposite ends of said spring for limiting the maximum extension thereof and the outward movement of said brush.

15 9. In an ignition distributor, a current distributing rotor, an insulating plate surrounding the axis of rotation of said rotor at one side thereof, at least two concentric conducting rings on said plate, an insulating block on the other side of said rotor, at least two concentric rings of angularly spaced contacts on said block, means on said rotor at one side of said axis for conducting current from one of said conducting rings to one of said rings of contacts, and means on said rotor at the other side of said axis for conducting current from the other of said conducting rings to the other of said rings of contacts.

20 45 10. In apparatus of the class described, a casing member, a rotatable shaft journaled in said member, at least one circuit breaker adjustably mounted on said member, a cam keyed to said shaft for rotation therewith for periodically separating the contact points of said circuit breaker during a predetermined angular rotation of said shaft, a current distributing rotor mounted on said shaft for rotation therewith, a plate mounted on said casing member for angular adjustment about the axis of rotation of said shaft, and reference marks on said rotor and said plate adapted to be aligned with each other at the instant said contact points are separated during said predetermined angular rotation of said shaft.

25 60 11. In apparatus of the class described, a casing member, a rotatable shaft journaled in said member, a plurality of circuit breakers adjustably mounted on said member, cam means mounted on said shaft for rotation therewith to periodically separate the contact points of each of said circuit breakers during predetermined angular movements of said shaft, a current distributing rotor mounted on said shaft for rotation therewith, a plate mounted on said member for angular adjustment about the axis of rotation of said shaft, a reference mark on said plate adapted to be aligned with a reference mark on said rotor at the instant the contact points of one of said circuit breakers are separated during a predetermined angular rotation of said shaft, and addi-

tional reference marks on said plate for use in conjunction with the reference mark on said rotor for properly adjusting the other of said circuit breakers relative to said one circuit breaker and said cam means for operating the same after said plate has been secured in position in proper relation with respect to said one circuit breaker.

12. In apparatus of the class described, a rotatable shaft, two circuit breakers mounted for adjustment relative to said shaft, cam means on said shaft for alternately periodically separating the contact points of said circuit breakers during the predetermined angular rotations of said shaft, a current distributing rotor mounted on said shaft for rotation therewith, a plate adapted for angular adjustment about the axis of rotation of said shaft, and reference marks on said plate

adapted for alignment with a reference mark on said rotor for indicating the proper positions of said rotor when said circuit breakers are initially opened by said cam means during predetermined angular rotations of said shaft.
